UNITED STATES PATENT OFFICE.

WILLIAM W. LASKE, OF BROOKLYN, NEW YORK, ASSIGNOR, BY MESNE ASSIGNMENTS,
TO REMINGTON RAND INC., OF NEW YORK, N. Y., A CORPORATION OF DELAWARE.

ZERO-SHUTTER CONTROL FOR PRINTING TABULATORS.

Application filed April 29, 1925. Serial No. 26,687.

The present invention relates to setting mechanism for machines controlled by perforated cards and relates more particularly to a control means for the zero shutters of a printing tabulator.

In printing tabulators or other machines employing type sectors which are positioned for predetermined type by registering stops selected by pins in accordance with the location of perforations in a card, it is usual to employ a pivoted shutter carrying a stop to cause the selector sector to correctly position the zero type for printing purposes. In such constructions it is necessary to shift the shutter out of the path of the selector sector holding means, whenever a type number or type character other than zero is to be set, thus for example when registering stop corresponding to the number "5" is set, the zero shutter is shifted to one side and the selector sector is free to swing past the zero stop and engage the set "5" register stop so that the "5" type is set for printing. With this arrangement it has been found that the zero shutter or shutters frequently are returned to their normal position before the sector has returned to its initial position and as a result the latch lug of the sector member impacts with the zero stop causing damage to both parts, disturbing the adjustment, and throwing the timing further out.

Some of the objects of the present invention are to provide an improved zero shutter control mechanism; to provide a hold out mechanism for zero shutters arranged to be controlled in timed relation to the movement of a selector sector of a print sector; to provide means positively insuring the return of selector sectors to normal or initial position before the zero shutters for such sectors are returned; to provide a hold out lock for zero shutters and means for releasing such lock after the printing sectors controlled thereby have returned to normal position; and to provide other improvements as will hereinafter appear.

In the accompanying drawings Fig. 1 represents a side elevation of a printing tabulator sector and its control adjuncts embodying one form of the present invention in zero shutter control means; Fig. 2 represents a plan of the control stop mechanism showing the zero shutter locking out means; Fig. 3 represents a section on line 3-3 of Fig. 1;

and Fig. 4 represents a detail in side elevation showing the locked position of the shutter mechanism.

Referring to the drawings, one form of the present invention is shown as applied to the control of the zero shutters 10 of a registering stop unit 11 by which the respective sectors 12 are positioned so that a predetermined type is actuated to print at the proper time in the cycle of operations. Generally considered the registering stop units 11 each consist of rows of stop pins 13 corresponding respectively to the numbers one to nine arranged consecutively, while at one end is a zero stop 14 carried by the shutter 10 in offset position so that normally the stop 14 is aligned with the stops 13 and consequently in position to hold the stop lug 16 on the adjacent selector sector 17. When the perforated card, which controls the setting of the stops 13 by raising one of them (as determined by the card punching) into the path of the lug 16, is punched in the zero position there is no movement of the corresponding shutter and the selector control sector 17 is held so that the sector 12 is located in its neutral non-printing position. On the other hand when a perforation corresponding to any one of the other stop pins is punched in a column of the card, the zero shutter 10 will be shifted, by the setting of the registering stop pin, out of the path of the sector lug 16 so that the selector control sector 17 is released to swing until its lug 16 abuts the registering stop 13 which is set. This brings the selected type of the sector 12 to its printing position.

The type sector shown is provided with twenty-three type elements for printing the alphabet. This sector and its controlling means are shown and described in U. S. Letters Patent No. 1,624,956 granted to W. W. Lasker, April 19, 1927. A more complete description of a type sector of this general type is found in U. S. Letters Patent No. 1,274,528 granted August 6, 1918 to C. Foster.

The construction of the shutters 10 and their relation to the stop pin 13 is such that the setting of any pin 13 in registering position causes the shutter for that pin row to be rocked on its pivots to release its zero stop 14 from the sector 17 so that the latter is free to travel until its lug 16 abuts the set stop pin 13. Each of the shutters 10 has a pro-

jecting lip 18 to be engaged by an end of a kick spring 20 which has its other end fast to a fixed part. Thus there are as many springs 20 as there are shutters 10 and all are under sufficient tension to normally hold the shutters in zero position and act to return them after movement out of position caused by the setting of a number stop pin 13.

For the purpose of locking the shutters 10 in the position each takes when a number register stop pin is set in the adjacent row, there are a plurality of bell crank detents 21 all mounted for separate pivotal movement upon a common rod 22 so that one end 23 of each is alined with and in close proximity to the normal position of the shutter controlled thereby. The opposite end of each of the detents 21 is held in contact with a restoring rod 24 by separate coil springs 25 interposed between the respective detents 21 and a rod 26. The two rods 24 and 26 are supported in parallel relation between two arms 27 which are fixed to a rock shaft 28 the latter receiving its motion from a link 29 joined to a push bar 30. The outer end of the push bar 30 is held by a lost motion connection, in the form of a pin 31 and a slot 32, in the path of a stud pin 33 projecting laterally from an arm 34 which is fast on the main rock shaft 35.

In the operation of the device the register stop pins 13 are operated and set in the usual manner in accordance with the perforations in the control cards, and the sectors 12 are released to be brought to stop position with the type corresponding to the set stop pins in printing position. The raising of a stop pin 13 in any of the rows causes the zero shutter for the set pin row to be swung back out of the path of the selector sector so that the latter is free to travel until it abuts the set stop. The timing of the main shaft 35 is such that the pin 33 moves out of the path of the end of the push bar 30 so that the latter is free to move to the right as seen in Fig. 1, thus removing the pressure of the restoring rod 24 from the detents 21 so that those detents 21, from the path of which the shutters have been removed, are swung clockwise by the action of their springs 25 to thus respectively lock their shutters in abnormal position. By this means the shutters 15 are prevented from returning to normal position when the set stops 13 are returned and cannot therefore get in the path of the returning selector sectors.

As the main shaft 35 causes the positive return of the sectors it is arranged so that the pin 33 on the arm 34 does not engage the push bar 30 until the sectors 12 and 17 have reached the end of their return stroke. When this occurs the push bar 30 is moved to the left as seen in Fig. 1 to thereby rock the shaft 28 and cause the restoring rod 24 to engage and swing such detents as are in locking position back to normal position removed from the path of the respective set shutters

10. The release of the shutters 10 allows the springs 20 to function and return the shutters so that the zero stops 14 thereof are in holding position in front of the shutter lugs 16.

It will now be apparent that a complete unitary control has been provided for coaction with the zero shutters of a selecting unit for print or type sectors whereby a positive timing relation is established between the return movement of the print and selector sectors and the zero shutters so that the former are insured of return to normal position before the latter are returned.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. In combination, a movable part, selecting members for positioning said part in any one of a number of predetermined positions, a shutter device for holding said part in initial position, means for shifting said device out of the path of said movable part when one of said selecting members functions, and means holding said device in shifted position until said part returns to initial position.

2. In combination, a movable part, selecting members for positioning said part in any one of a number of predetermined positions, a stop arranged to latch said part in initial position, means for shifting said stop to release said part, means for holding said stop in shifted position, and means for releasing said holding means to cause said stop to return to latching engagement with said part.

3. In combination, a movable part, selecting members for positioning said part in any one of a number of predetermined positions, a zero stop arranged to latch said part in zero position, means to shift said stop to release said part when a selecting member is actuated, means for holding said zero stop in shifted position, and means for releasing said holding means at a predetermined time in the stroke of said moving part.

4. In combination, a movable part, selecting members for positioning said part in any one of a number of predetermined positions, a zero stop arranged to latch said part in zero position, means to shift said stop to release said part when a selecting member is actuated, and means for holding said zero stop in shifted position until said movable part has returned to normal position.

5. In combination, a type sector, means for controlling said sector, a stop for holding said controlling means inoperative, means for shifting said stop to release said controlling means for operation of said sector, and

means operative until after the return of said sector control means for holding said stop in shifted position.

6. In combination, a type sector, means including a lug for controlling said sector, a stop arranged in the path of said lug and normally holding said controlling means inoperative, means for moving said stop out of the path of said lug under certain conditions to release said controlling means for operation of said sector, and means operative until said lug returns to normal position for holding said stop out of the path of said lug.

7. In combination, a type sector, means including a lug for controlling said sector, a plurality of aligned character stops arranged respectively to be projected into the path of said lug, a pivoted shutter in close proximity to said character stops, a zero stop on said shutter normally engaged by said lug to hold said controlling means in zero position, means for shifting said shutter to release said zero stop when a character stop is actuated, and means for locking said shutter in shifted position.

8. In combination, a type sector, means including a lug for controlling said sector, a plurality of aligned character stops arranged

respectively to be projected into the path of said lug, a pivoted shutter in close proximity to said character stops, a zero stop on said shutter normally engaged by said lug to hold said controlling means in zero position, means for shifting said shutter to release said zero stop when a character stop is actuated, means for locking said shutter in shifted position, and means for releasing said locking means at a predetermined time.

9. In combination, a type sector, means including a lug for controlling said sector, a plurality of aligned character stops arranged respectively to be projected into the path of said lug, a pivoted shutter in close proximity to said character stops, a zero stop on said shutter normally engaged by said lug to hold said controlling means in zero position, means for shifting said shutter to release said zero stop when a character stop is actuated, means for locking said shutter in shifted position, and means for releasing said locking means when said sector control lug has returned to a position back of said zero stop.

Signed at Philadelphia, in the county of Philadelphia and State of Pennsylvania, this 9th day of April, 1925.

WILLIAM W. LASKER.
